UNITED STATES PATENT OFFICE

ALPHONSE O. BRUNGARDT, OF BROOKLINE, MASSACHUSETTS

PIPE WRENCH

Continuation of application Serial No. 461,062, filed June 14, 1930. This application filed March 10, 1932. Serial No. 598,083.

This invention relates to wrenches and more particularly to forged steel wrenches of the "Stillson" type and is a continuation of my copending application, Serial #461,062, filed June 14, 1930.

An object of the invention is to provide a forged wrench of exceptional strength and durability having relatively few parts; one which is of relatively light weight and cheap to manufacture; and one in which the jaw action is such as to permit the wrench to be applied to the work to grip the same and be released therefrom without the necessity of careful adjustment of the jaw members, and likewise one which permits quick gripping or releasing of the work.

With present day pipe wrenches it is necessary to adjust the gripping jaws of the wrench to fit the work very carefully and accurately, due partly to the very limited action of the movable jaw relatively to the fixed jaw. This is, of course, objectionable, since it requires time under difficult conditions, and it is often impossible to effect the adjustment without making several attempts at it.

Wrenches made in accordance with my invention may be formed of carbon or alloy steels by a forging process. Such steels have sufficient strength to withstand the severest sort of service and are much lighter than present day cast wrenches which, in order that they may approach the strength of forged wrenches, are necessarily heavier and unwieldy in use. Moreover, these cast wrenches require steel bits or jaws, since teeth of sufficient strength and hardness cannot be made from cast material.

Attempts have been made to form the blanks comprising the handle and frame by forging, after which the jaw channel has been made by drilling, broaching and milling the frame. These drilling, broaching and milling operations are very expensive and make the cost of the wrenches prohibitive.

Wrenches made in accordance with my invention have a wholly new jaw action not present in any of the known wrenches. This new action obtained permits the application of the wrench jaws to the work without the necessity of a fine adjustment of the movable

jaw member. Normally, the shank of the movable jaw member is held in spaced relation to the bar and bodily against the far side of the channel to insure a relative positioning of the shank and bar to maintain the normal 55 predetermined desired angle between the jaws as will hereinafter be described. When the jaws are engaged with the work and the initial load applied to the end of the bar or handle, the movable jaw member moves toward the bar away from the far side of the channel bodily without tilting until the adjusting nut engages the walls of the window. On further application of the load, the nut serves as a pivot for the jaw during its oscillating or tilting movement, thus permitting the head of the movable jaw to tilt forward toward the bar. When the load is released, the tendency of the movable jaw member under the action of the spring, is to 60 move away from the bar and return to its normal position, and the head of the movable jaw member may tilt past its parallel position away from the bar. Thus, it will be seen, that by using my improved double 65 acting spring, the head of the movable jaw member is capable of maximum movement toward and away from the bar. The action described permits almost instant gripping and releasing of the work.

The invention will be more fully understood from the following description when taken in connection with the accompanying drawings, and the novel features thereof will be pointed out and clearly defined in the 70 claims at the close of this specification.

In said drawings:

Fig. 1 is a fragmentary side elevation of my improved wrench with the parts in normal positions, and showing my improved 75 spring in broken lines.

Fig. 2 is a section taken substantially along the line 2-2 of Fig. 1, looking in the direction of the arrows.

Fig. 3 is a perspective view of the spring 80 of Figs. 1 and 2.

Figs. 4, 5, 6 and 7 are side elevational views partly in section, illustrating the action of the jaws during the gripping and releasing 85 of the work.

Figs. 8 and 9 are side elevational views, partly in section, illustrating further, the action of the jaws in gripping work of a larger diameter, without further longitudinal adjustment of the movable jaw member.

Fig. 10 is a fragmentary side elevation, illustrating a slightly modified form of spring and assembly.

Fig. 11 is a perspective view of the spring of Fig. 10.

Before explaining in detail the present invention, it is to be understood that the invention is not limited in its application to the details of construction and arrangement of parts illustrated in the accompanying drawings, since the invention is capable of other embodiments and of being practiced or carried out in various ways. Also it is to be understood that the phraseology or terminology employed herein is for the purpose of description and not of limitation, and it is not intended to limit the invention beyond the terms of the several claims hereto appended as considered in view of the prior art and the requirements thereof.

Referring now particularly to Figs. 1 to 9 inclusive, my improved wrench is shown as a whole at 10, and comprises, preferably, a forged steel bar or handle 11 having a fixed jaw 12 and an integral frame or housing, shown as a whole at 13.

The frame is provided with a longitudinal channel 14, the walls of which are preferably parallel and at a certain specified angle to the fixed jaw 12 as will be hereinafter described. The frame 13 is also provided with a transverse window or opening 15 which may be wholly or partially enclosed and which intercepts the channel 14. The window, as shown, is substantially V-shaped, having front and rear walls 16 and 16a respectively, which converge toward the bar 11. It will be seen that the lower ends of the walls 16 and 16a become parallel at the points 16c for the purpose of insuring the freedom of up and down movement of the adjusting nut, to be presently described. The bar is also provided with a longitudinally extending spring groove 17 which extends throughout the length of the frame and is positioned below the inner or lower wall of the channel. The frame is provided on opposite sides or faces adjacent the walls 16 and 16a, with pairs of ears or projections 20 and 21 which form outward extensions or continuations of the front and rear window walls, respectively.

The wrench also includes a movable jaw member shown as a whole at 25, having a head 26, provided with a jaw face or integral bit 27, and a shank 28 provided with a screw thread 29. The shank 28 is positioned within the longitudinal channel 14 and is movable therein towards and away from the bar, the channel 14 being wider than the shank to permit such movement. The shank is also capa-

ble of longitudinal adjustment with respect to the longitudinal axis of the bar, by means of an adjusting nut 30 which is internally threaded and adapted to engage the screw threads 29. The adjusting nut 30 is positioned within the window or opening 15 and is preferably round, having smooth or plain surfaces on each side to allow it to move freely in the window, and is also provided with a peripheral centrally disposed depressed or countersunk knurled band or portion 30a. The purpose of providing the depressed or countersunk knurled band, which is flush with the smooth periphery of the nut, is to provide a smooth surface for engagement with the wall of the window. When the parts are assembled, as shown by Fig. 1, the ears or projections 20 and 21 extend laterally beyond the periphery of the nut 30, and prevent accidental adjustment of the movable jaw member when the wrench is laid on a bench or floor. When the movable jaw member 25 is oscillated or tilted within the housing relative to the bar or handle, the front walls 16 and their extensions or ears 20, serve as bearings for the smooth front side of the adjusting nut.

In accordance with my invention, it is desirable to maintain the movable jaw member 25 spaced from the inner side of the channel and bodily against the far side thereof, and also to resiliently support the jaw member so that it can be moved toward or from the bar during the action of the jaws when gripping or releasing the work. In order to accomplish this, I have provided an improved double acting spring member best shown in Fig. 3 and indicated as a whole by the reference numeral 35. This spring member is preferably in the form of a leaf, bent to provide a centrally depressed flat section or portion 36 and upwardly bent portions 37 which are curved outwardly and extended to provide flaring end portions 38. The tips of the end portions 38 are bent back slightly as shown at 39 so that when the spring is assembled with the wrench, the end portions 38 will ride freely in the groove 17. As seen by Fig. 1, the spring, when assembled in accordance with the form of my invention shown in this figure, is positioned between the bar and shank of the movable jaw member, with portions of its outwardly flared end sections 38 engaging the screw threads 29 on the shank, and with its extreme ends in engagement with the groove 17. With my improved spring, having its ends 38 engaging the spring groove 17 at all times, the movable jaw member is capable of the desired movements. When the spring maintains the shank at the far side of the channel from the spring as illustrated in Figure 1, the shank is maintained substantially in parallelism with the portion of the bar near the shank and the jaws are thus maintained by the spring because of its re-

sistance to tilting movement in their predetermined angular relation. This angular relation is determined by the angle at which one of the jaws, in the present instance the jaw 12, 5 is cut with reference to the length of the bar. As will be understood, this angle is more or less conventional and is usually of one about 8° as illustrated. As a consequence, the spring, although permitting the in- 10 ward bodily movement of the shank, resists angular or tilting movement during the bodily movement until the nut engages the bar, whereupon the nut serves as a pivot or fulcrum for angular or tilting movement 15 during further application of turning pressure to the wrench. This turning or tilting movement is limited by the engagement of the nut with the frame, as described.

In assembling the wrench, the spring 35 20 is slipped into position within the frame 13 through the groove 17 until it assumes the position to which it is shown in Fig. 1. The adjusting nut 30 is then inserted in the window or opening 15 and the jaw shank 28 25 inserted in the channel 14 until the inner end thereof engages the nut. By rotating the nut, the shank is drawn inwardly or downwardly, moving the jaw or bit 27 toward the corresponding jaw or bit 12.

30 Referring now to Figs. 4 to 7 inclusive, which illustrate the various positions assumed by the parts during use of the wrench, it will be seen in Fig. 4 that the wrench jaws have been engaged with a pipe 100. The 35 parts are in their normal positions, with the shank of the movable jaw member engaging the outer wall of the frame or housing, the spring 35 serving to maintain the parts in this position. When a load is applied to 40 the end of the bar or handle as shown by the arrow in Fig. 5, the movable jaw member and adjusting nut move downward or inward toward the bar, the spring maintaining the jaw member parallel with the sides 45 of the channel to insure the relative positioning of the shank and bar to maintain the normal predetermined desired angle between the jaws as described. During this movement of the jaws the lower portion of the face of the nut 30 adjacent the front wall 16 of the window slides across the front wall 16 until the periphery of the nut engages the lower wall of the window. At the extreme 50 inner position of the shank, it will be seen that the spring is compressed and housed within its groove 17, so that the spring cannot be pinched between the nut and the bar or the shank and the bar. The parts are now ready for the application of an additional load to the bar.

55 Referring to Fig. 6, the arrow indicates that such load has been applied, and in this figure it will be seen that the head 26 of the movable jaw member has moved toward the fixed jaw and 60 that the shank has oscillated or tilted

against the action of the spring toward the bar, and out of parallelism with the longitudinal axis of the bar. During this tilting or oscillating movement of the jaw member the nut which has, as described, one portion of one face in engagement with the window wall 16 of one portion of its periphery engaging the lower wall of the window, serves as the pivot. With the parts assuming the position shown, the front face of the adjusting nut has a full bearing across the entire front wall 16 of the window and its corresponding ears or projections 20, the spring being compressed at its forward portion. It will be noted that the spring is not pinched by the jaw shank or nut and is not subjected to any crushing force, due to the fact that the spring moves into the spring groove which is below the inner wall of the channel and because the nut seats on the inner wall of the window, which is above the channel inner wall. In other words, when the movable jaw member and nut are moved toward the bar, the spring recedes into its groove or slot and is, therefore, not subjected to any pinching or crushing action by the shank or nut.

70 The angularity of the window walls 16 and 16a with relation to the described parallel sides of the channel is such that when the movable jaw is tilted to its extreme forward or backward position the jaw threads 29 do not bear upon the walls of the channel at the points A and B, Fig. 6, or C and D, Fig. 7, and, as shown, a slight clearance may 75 exist at these points. The nut acting against the window wall 16 forms a stop in the full load position and takes the strain which would otherwise be borne by the threads. The threads are thus protected at all times, 80 which is essential, since if they were damaged through contact with other parts of the wrench, accurate adjustment of the movable jaw member would be impossible.

85 During the use of a pipe wrench it is necessary that slipping of the wrench jaws on the pipe wall be avoided and a secure bite obtained. A certain amount of crushing force is necessary to effect this gripping action, but this force should never be sufficient 90 to permanently injure the pipe or other article being gripped.

95 With my improved wrench the jaw moves from its parallel position when an additional load is applied and the pipe is gripped in a forward position with the movable jaw 25 tilted forward, so that the nut 30 has a full bearing on the window wall 16, as shown in Fig. 6. In this position of the jaw the gripping action is adequate but the crushing force is negligible. If, on the other hand, the jaw were tilted from the parallel position to a backward position with the pipe contacting with the shank of the jaw, sufficient 100 crushing strain could be exerted to perma- 105

nently injure the pipe. With my invention the jaw in normal use does not grip the pipe in this backward position and thus excessive crushing is avoided.

5 Accordingly, the spring 35 is formed with sufficient stiffness to normally press the jaw 25 against the long bearing of the outer wall of the frame. Due to its inherent stiffness and also the fact that its pressure is applied 10 through a relatively long moment arm, the spring strongly resists backward deflection of the jaw when gripping the pipe.

It is also desirable that a positive releasing action of the jaw shall occur when the 15 load on the bar is reversed so that the wrench may be freely ratcheted on the pipe for taking a new bite. This is accomplished by the action of the spring which is powerful enough to immediately assist manual force 20 applied to the bar in a reverse direction, in view of the fact that the tendency of the spring is to hold the jaw in the described parallel position with the shank pressing against the outer wall of the frame.

25 When the load is released from the bar and the bar moved in the opposite direction to disengage the jaws from the work, the parts may assume the positions in which they are shown in Fig. 7, the movable jaw member having been tilted in the opposite direction from its maximum closed position back into parallel position and beyond to its maximum open position.

In Figs. 8 and 9, I have shown two positions of the parts of the wrench during the engagement and gripping action of the jaws with the pipe 200. The pipe 200 is of larger diameter than the pipe 100 of the preceding figures, and the wrench is applied thereto 30 without changing the adjustment of the movable jaw member longitudinally of the bar. In Fig. 8, the jaws are shown as just engaging the work, and in Fig. 9, the jaws have been forced over the work until the pipe has 35 been gripped by the jaws, the arrow indicating the movement of the wrench relative to the pipe. Thus, it will be seen, that when the jaws are applied to work having a diameter greater than the space between the jaws 40 when in their normal positions (Fig. 8) the movable jaw member 25 is tilted or oscillated out of its normal position, that is, parallel with the sides of the channel, with the nut serving as a pivot. In this tilted position, the nut lies in engagement with the lower window wall 16a. With the parts in 45 this position, the rear or inner end portion of the spring 35 is compressed. When a load is applied to the end of the handle, the tendency of the movable jaw member is to move 50 from its position of Fig. 9 toward the bar, i. e., parallel with the sides of the channel, during which movement the nut also acts as the pivot. In other words, during the application of the load to the bar, the parts are

5 moved toward the position in which they are shown in Fig. 5. On further application of the load, the movable jaw member will tend to tilt beyond its parallel position and toward a position similar to that shown 70 in Fig. 6, although, due to the larger diameter of the pipe 200, the parts never actually assume the position in which they are shown in Fig. 6. In this later position of the parts, the forward or outer end portion of the spring is compressed. Upon releasing the load from the bar and moving the end of the bar outward as shown by the arrow in Fig. 7, the parts again assume the positions in which they are shown, first in Fig. 9, and later in 80 Fig. 8, the latter position being the normal position of the parts.

By providing a double acting spring, such as the spring 35, it will be seen that the movable jaw member is permitted to tilt or oscillate toward or away from the bar and out of its normal parallel position to the extent of approximately four degrees in either direction, and that with the normal use of the wrench on work of a size substantially equal 90 to the space between the jaw members, the initial movement of the movable jaw member toward the bar is always bodily or untilted upon the initial application of a load to the bar. Moreover, it will be seen that the adjusting nut serves as a pivot for the movable jaw member during its tilting or oscillating movements.

In Fig. 10 I have shown a modified form 100 of spring in which the action of the parts is the same as in the preceding form. In this form, however, the wrench bar 211 is provided with a longitudinal spring groove 270 and is additionally provided with a spring seat or recess 271, located within the slot and being substantially in the form of a Woodruff key-slot.

My improved spring, used in a wrench of this form, is best shown as a whole in Fig. 11 and is indicated by the reference numeral 400. The spring is preferably in the form of a leaf bent to provide a central convex or outwardly curved portion 401 and oppositely curved outwardly flaring end portions 402. The extreme outer ends of the portions 402 are bent back slightly at 403 to provide rounded ends. On opposite sides of the concave or curved portion 401, the spring is provided with spaced pairs of upstanding lugs or projections 404. In assembling the wrench parts (Fig. 10) the spring 400 is slid through the groove 270 until the portion 401 thereof engages and is seated in the recess 271. The adjusting nut 30 is then inserted in the window 15 and the inner end of the shank 28 is brought into engagement with the nut, the internal threads on the nut cooperating with the threads 29, so that on rotation of the nut to the right the shank is drawn into and through the longitudinal channel 14. When 110 115 120 125 130

the nut is in place in the window, it will be seen that the lugs or projections 404 lie on opposite sides of the nut and engage its opposite faces, to prevent accidental displacement of the spring. In this form, the central portion 401 of the spring is seated in the recess 271, and the end portions 402 engage the screw threads 29 of the shank. In this connection, the purpose of forming the bent back or rounded ends 403 will be apparent. By so forming the ends, the threads 29 will slide freely over the spring during its movement by means of the adjusting nut 30, and also during tilting or oscillation of the movable jaw member. The action of the movable jaw member, the adjusting nut and the spring is identical with the action of the corresponding parts of the wrench shown in Figs. 1 to 9, inclusive. It will be noted that the spring 400 maintains the shank normally in contact with the outer wall of the frame or housing so that the normal predetermined desired angle is maintained between the jaws. The spring 400 also provides means for maintaining the movable jaw member in this described parallel position during the movement of the jaw member toward the bar when an initial load is applied to the end of the bar, in exactly the manner as illustrated in Fig. 5.

I claim:—

1. A pipe wrench comprising a bar having a jaw and a frame, said frame having a longitudinal channel therein, a movable jaw having a shank extending through the channel, said channel being wider throughout its length than the shank sufficiently to permit both bodily and angular movements of the shank, and a spring normally tending to hold the shank bodily against the far side of the channel to insure a relative positioning of the shank and bar to maintain the normal predetermined desired angle between the jaws and yieldable to permit movement of the shank away from said side toward the other side of the channel but tending to prevent any angular shift of the shank during such movement.

2. A pipe wrench comprising a bar having a jaw and a frame, said frame having a longitudinal channel therein, a movable jaw having a shank extending through the channel, said channel being throughout sufficiently wider than the shank to permit a bodily movement transversely of the channel without tilting of the shank, a spring serving to hold the shank bodily against the far side of the channel and yieldable to permit bodily movement of the shank away from said far side toward the other side while resisting tilting of the shank, adjusting means on the shank engageable with the bar during said bodily movement to limit such movement before engagement with the bar, providing a fulcrum for rocking movement of the shank

in said channel upon completion of said bodily movement, the bar carrying a portion serving, by engagement with said adjusting means during said rocking movement, to limit the latter before the rocking of the shank causes it to bear against the bar or frame. 70

3. A pipe wrench comprising a bar having a jaw and a frame rigid with the bar and jaw, said frame having a longitudinal channel therein, a movable jaw having a shank extending through the channel, said channel being throughout sufficiently wider than the shank to permit a bodily movement transversely of the channel without tilting of the shank, a spring disposed between the shank and bar serving to hold the shank bodily against the far side of the channel and yieldable to permit bodily movement of the shank away from said side toward the other side while resisting tilting of the shank, adjusting means on the shank engageable with the bar during said bodily movement to limit such movement before engagement of the shank with the bar, said means, by its engagement with the bar, providing a fulcrum 80 for rocking movement of the shank in said channel upon completion of said bodily movement, the bar carrying a portion serving, by engagement with said adjusting means during said rocking movement, to limit the latter 85 before rocking of the shank causes it to bear against the bar or frame. 90

4. A pipe wrench comprising a bar having a jaw and a frame rigid with the bar and jaw, said frame having a longitudinal channel therein, a movable jaw having a shank extending through the channel, said channel being throughout sufficiently wider than the shank to permit a bodily movement transversely of the channel without tilting of the shank, a spring disposed between the shank and bar serving to hold the shank bodily against the far side of the channel and yieldable to permit bodily movement of the shank away from said side toward the other side 100 while resisting tilting of the shank, adjusting means on the shank engageable with the bar during said bodily movement to limit such movement before engagement of the shank with the bar, said means, by its engagement 105 with the bar, providing a fulcrum for rocking movement of the shank in said channel upon completion of said bodily movement, the bar carrying a portion serving, by engagement with said adjusting means during said rocking movement, to limit the latter 110 before rocking of the shank causes it to bear against the bar or frame. 115

5. A pipe wrench comprising a bar having a jaw and a frame, said frame having a longitudinal channel therein, a movable jaw having a shank extending through the channel, said channel being throughout sufficiently wider than the shank to permit a bodily movement transversely of the channel without tilting of the shank, a spring disposed in a groove and having portions extending therefrom which are movable into the groove whereby to permit movement of the shank toward the spring without pinching the spring. 120

5. A pipe wrench comprising a bar having a jaw and a frame, said frame having a lon- 130

itudinal channel therein and a window intersecting the channel, a movable jaw having a threaded shank extending through the channel, said channel being throughout sufficiently wider than the shank to permit a bodily movement without tilting of the shank transversely of the channel, a spring disposed between the shank and bar serving to hold the shank bodily against the far side
5 of the channel and yieldable to permit bodily movement of the shank away from said far side toward the spring side while resisting tilting of the shank, an adjusting nut on the shank within said window engageable with
10 the bar during said bodily movement to limit such movement before engagement of the shank with the bar, said nut by engagement with the bar, providing a fulcrum for rocking movement of the shank in said channel
15 upon completion of said bodily movement, the nut serving by engagement with said frame during said rocking movement to limit the latter before the rocking of the shank causes its threads to bear against the bar or
20 frame.

In testimony whereof I affix my signature.
